UNITED STATES PATENT OFFICE.

FRED K. LEWIS, OF ASHTABULA, OHIO.

TOP FOR VEHICLES AND THE LIKE.

Application filed May 7, 1919, Serial No. 295,404.

To all whom it may concern:

Be it known that I, FRED K. LEWIS, a citizen of the United States, and a resident of Ashtabula, county of Ashtabula and State of Ohio, have invented a new and useful Improvement in Tops for Vehicles and the like, of which the following is a specification, the principle of the invention being herein explained and the best mode in 10 which I have contemplated applying that principle, so as to distinguish it from other inventions.

The object of the present invention is to provide an outrigger structure for automobile tops of the so-called "one man" type, which will be capable of considerably more longitudinal extension than in present designs, while still retaining the essential feature of supporting the top structure wholly 20 from a single main bow. More particularly the object is to provide a structure of the character in question, which may be supported from a single rearwardly inclining main bow, so that when the top is extended the 25 entire tonneau space forwardly of such main bow will be clear of any obstruction, even where such tonneau is a two-seated one. A further object is to provide a structure that may be readily manipulated to either fold 30 or unfold as desired, without it being necessary for the operator to leave the tonneau.

To the accomplishment of the foregoing and related ends, the invention, then, consists of the means hereinafter fully described 35 and particularly pointed out in the claims, the annexed drawing and the following description setting forth in detail certain mechanism embodying the invention, such disclosed means constituting, however, but 40 one of the various mechanical forms in which the principle of the invention may be used.

In said annexed drawing:—

Fig. 1 is a side elevational view of a top supporting structure embodying my present improvements, such top being shown as mounted on an automobile body or tonneau of conventional form; and Fig. 2 is a similar side elevation showing the top and such supporting structure in partially collapsed 50 or folded condition.

It is of course a matter of indifference whether the top is used on automobile, motor-boat or otherwise, and, depending 55 upon its longitudinal extent, a smaller or larger number of bows, in addition to the

outrigger structure of present interest, may be utilized. It will also be understood that the term "bow" is used herein inclusively to designate not merely the wooden bow proper, but also the metallic sockets carrying the same, these parts when regarded in side elevation constituting the equivalent of the so-called "sticks," as they are called in the old wood structure. It is accordingly a 60 matter of convenience to refer to the parts in the singular, as though the structure lay all in a single vertical plane, since the parts of interest do actually lie in such a plane.

As previously indicated, the top covering 70 1 is designed to be entirely supported through an appropriate outrigger structure from a single main bow 2. The latter, which is of substantial construction in view of the weight it is thus designed to carry, is pivotally supported upon or attached to the body at the point 3 in the usual manner, so that it may be laid down and supported in a substantially horizontal plane when the top is 75 not in use. Normally, in the extended or open condition of the top, said main bow 2 inclines rearwardly at an angle of approximately forty-five degrees to the horizontal, being held from rising higher by the top covering, or rather by special straps (not 80 shown) or extensions of the longitudinal strainers which, as is well known, are used to connect the bows together and provide supporting means for the top covering intermediately between said bows. For the 85 purpose in hand such straps or strainers may be regarded as a part of the covering material.

The outrigger structure comprises a main articulated auxiliary bow, or, as it is sometimes called, outrigger bow 6, the latter term referring more particularly to the outer portion or bow 7 proper, which is secured to the main bow 2 by means of an arm 8 (one on each side of course) pivotally attached to said main bow and to the rear end of such outrigger bow, and so constituting the inner portion of said articulated auxiliary bow 6. The point of attachment of this arm to the main bow is preferably in line with, or just above, the side edge of the cover, so as to be hidden by the latter, and the joint 9 between said arm and the outrigger bow is a rule joint disposed so as to prevent further bending of the arm in question, when extended in horizontal fashion, as in the open condition of the top illustrated in Fig. 1. 95 100 105 110

Pivottally attached to the arm 8 is a supplemental bow 10 that in such open condition of the top is designed to extend forwardly at an angle with respect to said arm so as to support the cover 1 at a point approximately midway between the main bow 2 and the outrigger bow 7. Operatively connecting said supplemental bow with the main bow 2 and outrigger bow 7 is a link 10 comprising two parts pivotally connected together. As shown, the forward part 11 is pivotally connected to said outrigger bow at a point 12 just beyond the joint 9 in the latter and to said supplemental bow at a point 13 suitably spaced from the point of attachment of said bow on arm 8; while the rear part 14 of said link or brace has its one end attached to said forward part 11 at a point 15 slightly in front of the point 20 13 of attachment of the latter to supplemental bow 10, and its other end pivotally attached to the main bow, or preferably, as illustrated, to a bracket 16 on the front face of said main bow which at the same time 25 provides means for attachment to the latter of the arm 8. The upper portion of this bracket is bent forwardly at an angle approximating a right angle, so that the point of pivotal attachment of said link-part 14 30 will lie substantially directly above the point of attachment of said arm 8 in the open position of the top, i. e. a line passing through the two points in question will lie at approximately right angles to the median 35 line of main bow 2.

The forward link-part 11, which may also be regarded as a lever, extends beyond the point 12 of its pivotal attachment to outrigger bow 7, so that its corresponding end 40 projects a trifle below the plane of said bow when the top is open, and attached to such end is a second outrigger bow 17, which supports the extreme forward portion of the top covering 1. There are thus provided in 45 effect two articulated outrigger bows which support the forward portion of the top covering and permit of a corresponding increase in the longitudinal extent of the latter without requiring a separate forward 50 support resting on the vehicle body. This second outrigger bow 17 is freely pivotally connected with said link-part 11, it being observed that the position of the joint is determined by the angular position of the link, the latter being locked in proper place, when the top is open, by the action of a stop 18 on the arm 8 which engages with supplemental bow 10 and limits its position 55 when the top is open. A separate link 19, however, is desirably utilized to connect outrigger bow 17 with the main outrigger bow 7, so that it may be supported therefrom without imposing too much strain on the cover material between the two bows.

Said link 19 furthermore serves to cor-

relate the movement of the two outrigger bows when the top is being folded, as will be evident from an inspection of Fig. 2. This figure clearly illustrates the manner in which the other component parts of the top supporting structure fold up; thus it will be seen that the link-part 11 and said link 19 maintain the supplemental bow 10 and the two outrigger bows 7 and 17 in substantially parallel arrangement during the folding operation, and of course equally so during the unfolding of the top. The link-part 14 not only serves to sustain the whole outrigger structure, when extended, in proper angular relation to the main bow 2, but by virtue of its point of connection with the forward link-part 11 and with the bracket 16, it is enabled to fold up parallel with the other parts just referred to. It should be noted in passing that the rear end of the forward link-part 11 curved downwardly or dropped a trifle, so that its point 13 of attachment to supplemental bow 10 lies below a line passing through the link-parts in their extended condition.

The structure is thus seen to be unusually compact in its folded condition, and yet when extended an adequate support for a top of considerable longitudinal extent is provided without any obstruction in the way of a forwardly inclining main bow, or braces or links that lie below the side line of the top covering. The various component bows are joined together by the employment of a minimum number of connecting parts, which need not be of specially heavy construction, in order to afford a rigid and entirely satisfactory support.

It will be understood of course that when the top is extended, the second or extreme forward outrigger bow is attached or tied down to the wind-shield as indicated by the dotted line at the right of Fig. 1. The top, however, is self-supporting save as jars or the wind might tend to tilt it bodily about the single pivotal support 3 upon which the whole structure is sustained.

As in the foregoing description, the two bows 7 and 17 may be regarded as first and second outrigger bows in the order named, the first of said bows being of two-part articulated construction, and the second likewise of articulated construction but of more than two parts; in other words it is connected with the main bow through the medium of the two link-parts 11 and 14. The latter may also be regarded as constituting a flexible connection between the rear portion of the first-named outrigger bow, the main bow and the supplemental bow.

Other modes of applying the principle of my invention may be employed instead of the one explained, change being made as regards the mechanism herein disclosed, provided the means stated by any of the

following claims or the equivalent of such stated means be employed.

I therefore particularly point out and distinctly claim as my invention:—

5 1. In a top for vehicles and the like, the combination of a suitable standard; a two-part articulated outrigger bow having its rear portion pivotally attached to said standard; a supplemental bow pivotally attached to such rear portion; and a second articulated outrigger bow having its rear portion disposed to intersect the forward portion of said first outrigger bow and being pivotally attached thereto at such point 10 of intersection, such rear portion of said second outrigger bow comprising two pivotally interconnected parts, one such part being pivotally attached to said standard above the point of attachment of said first 15 outrigger bow thereto, and the other such part being pivotally connected with said supplemental bow.

2. In a top for vehicles and the like, the combination of a main bow; a two-part articulated outrigger bow having its rear portion pivotally attached to said main bow; a supplemental bow pivotally attached to such rear portion; a link pivotally attached to the forward portion of said outrigger bow and intersecting the same in the open position of the top; a second outrigger bow attached to the forward end of said link; and a second link pivotally attached at one end to said main bow, one of said two links being also pivotally attached to said supplemental bow and the other link to such one.

3. In a top for vehicles and the like, the combination of a main bow; a two-part articulated outrigger bow having its rear portion pivotally attached to said main bow; a supplemental bow pivotally attached to such rear portion; a link pivotally attached to the forward portion of said outrigger bow and intersecting the same in the open position of the top; a second outrigger bow attached to the forward end of said link, the rear end of the latter being attached to

said supplemental bow; and a second link pivotally attached at its respective ends to said first link and to said main bow. 50

4. In a top for vehicles and the like, the combination of a main bow; a two-part articulated outrigger bow having its rear portion pivotally attached to said main bow; a supplemental bow pivotally attached to such rear portion; a link pivotally attached to the forward portion of said outrigger bow and intersecting the same in the open position of the top; a second outrigger bow attached to the forward end of said link, 55 the rear end of the latter bending downwardly and being attached to said supplemental bow; a second link pivotally attached at one end to said first link forwardly of its point of attachment to said supplemental bow and at its other end to said main bow; and a third link directly connecting said second outrigger bow with the outer portion of said first outrigger bow. 60 63

5. In a top for vehicles and the like, the combination of a rearwardly inclined main bow; a two-part articulated outrigger bow having its rear portion pivotally attached to said main bow and thence inclining forwardly and upwardly in the open position 75 of the top; a supplemental bow pivotally attached to such rear portion; a second articulated outrigger bow extending substantially horizontally in such open position and having its rear portion pivotally attached to the forward portion of said first outrigger bow; and a bracket on said main bow projecting forwardly therefrom, the rear portion of said second outrigger 80 bow comprising two pivotally interconnected parts, one such part being pivotally attached to said bracket at a point substantially directly over the point of attachment of said first outrigger bow to said main bow in such open position and the other such 85 part being pivotally connected with said supplemental bow. 90

Signed by me this 1st day of May, 1919.

FRED K. LEWIS.
